UNITED STATES PATENT OFFICE.

HENRY HORAN, OF EAST ORANGE, NEW JERSEY, ASSIGNOR TO THE HART FORD CARPET COMPANY, OF HARTFORD, CONNECTICUT.

DESIGN FOR A CARPET.

SPECIFICATION forming part of Letters Patent No. 12,482, dated September 12, 1881.

Application filed August 9, 1881. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a prominent bouquet of roses and other 15 flowers, having projecting sprays of fern and other leaves, branches, buds, and lesser flowers. B is a smaller bouquet, composed of three prominent leaves that support a rose and a star-flower. A twig, a, extends from the bouquet B, and bears ornamental leaves and rich flowers. Other lesser bouquets and floral

groups, C D E F G, are scattered over the background. Between these several groups are seen cloud-like spots b b, made up of adjoining hexagons. These figures b serve to impart a degree of indefiniteness to the remaining figures and to take away their sharpness of outlines. 25

I claim—

1. The design for the ornamentation of a carpet, consisting of figures b b, substantially as shown. 30

2. The design for carpets, consisting of the figures A B a C D E F G, substantially as shown. 35

3. The design for carpets, consisting of the figures A B a C D E F G b, substantially as shown.

HENRY HORAN.
